UNITED STATES PATENT OFFICE.

HENRY M. VAN DEUSEN, OF WESTFIELD, MASSACHUSETTS.

DROP-TOP WHIP.

SPECIFICATION forming part of Letters Patent No. 769,516, dated September 6, 1904.

Application filed February 26, 1904. Serial No. 195,448. (No model.)

To all whom it may concern:

Be it known that I, HENRY M. VAN DEUSEN, a citizen of the United States, residing at Westfield, in the county of Hampden and State of Massachusetts, have invented certain new and useful Improvements in Drop-Top Whips, of which the following is a specification:

My invention relates to improvements in whips, more especially of that type which may be termed "express" or "drop-top" whips. Heretofore whips of this class or type have had their "top" formed of a core exclusively of "cloth," and it is with the view of overcoming certain disadvantages or objections thereto I have contrived the invention forming the subject-matter of this specification.

It has for its object, among other things, to provide for increased effectiveness and pliability, more especially as relates to the whip-top, without complicating the structural features thereof and also to lessen cost of manufacture and otherwise promoting utility and convenience.

Said invention consists of certain structural features, substantially as hereinafter more fully disclosed, and particularly pointed out by the claim.

In the accompanying drawings, illustrating the preferred embodiment of my invention, Figure 1 is a perspective view thereof. Fig. 2 is a view showing the core of the whip at one stage of the manufacture of the latter. Fig. 3 is an enlarged detail view with certain parts constituting the core of the whip-top shown detached or ripped for the fuller disclosure thereof. Fig. 4 is an enlarged cross-section through the finished whip.

In the carrying out of my invention I form the core 1^x of the handle or stock 1 preferably of wood in two sections or parts 1^a 1^b , the inner section 1^a being preferably tapered or vanished at its relatively outer end, as at 1^c , a suitable distance, which tapered portion is inserted and confined in any suitable way in a corresponding notch or socket 1^d , produced in one end of the section 1^b . The inner section 1^a may be and is preferably a stiff or

inflexible wooden piece, while the other section, 1^b , is of tough yielding or springy material and tapered to a very narrow outer end 50 to impart the requisite flexibility to that part of the stock as where it connects with the whip-top.

The whip-top 2 is formed of a core, preferably of manila fiber, hemp, sisal, or jute 55 and such like material, either in rope form or before the same has been caused to assume such form, preferably initially applied to the narrow tapering end of the stock core-section 1^b , to which it is suitably bound by twine or otherwise, and farther upward to this section 1^b is applied a strip of textile material 2^b, to which it is bound by wrapping with twine or otherwise. Said strip or textile material is also spirally carried and bound around said 60 core by continuing the aforesaid twine-wrapping operation until the entire core is compactly bound and brought within the required cross-sectional compass or area to form the whip-top. The stock and whip-top are all 70 now covered or inclosed and finished in the usual way, as shown, as well understood.

This invention provides for greatly simplifying the construction, especially of this class of whips, while the manila fiber, hemp, sisal, 75 or jute and such like material form a cheap and effective core for the whip-top, possessing it of greater or increased flexibility as compared to the way previously adopted in constructing the whip-top. The whip-top 80 falls gracefully or symmetrically from the stock and is especially desirable for express or drop-top whips, as above intimated.

When the drop top or lash is formed from a rope, as shown in Fig. 3, the part of the top 85 or lash employed to join it to the stock will be frayed out to the extent necessary, as shown at 2^a in said last-mentioned figure. In this case the core or body of the lash throughout will be formed of a simple rope, having 90 the usual whip finish. This form and mode of procedure in manufacture lessens the cost of construction, enhances the strength, and insures uniformity in size throughout the

length of the top or lash, points that are desirable in drop-top whips. For many purposes I desire to make the whip in this form.

Latitude is allowed as to details herein, as 5 there may be changes as circumstances suggest without departing from the spirit of my invention and the latter still be protected.

I claim—

10 A drop-top whip having a rigid stock and a flexible top formed of rope united to said

stock by a textile - material strip and cord wrapped around said stock and top, the whole having the usual exterior whip finish.

In testimony whereof I have signed my name to this specification in presence of two wit- 15 nesses.

HENRY M. VAN DEUSEN.
